UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRIC-LAMP SOCKET.

1,336,607.

Specification of Letters Patent. Patented Apr. 13, 1920.

Application filed January 29, 1915. Serial No. 5,055.

To all whom it may concern:

Be it known that I, REUBEN B. BENJAMIN, a citizen of the United States, residing at Chicago, in the county of Cook and State 5 of Illinois, have invented new and useful Improvements in Electric-Lamp Sockets, of which the following is a full, clear, concise, and exact description, reference being had to the accompanying drawing, forming a 10 part of this specification.

My invention relates to electric lamp sockets, and specifically to sockets for use in connection with a feed circuit comprising an inner insulated conductor and an outer bare 15 grounded conductor.

Among the objects of my invention are to provide a socket which shall be simple in construction, easy to manufacture and efficient in use and operation.

20 Further objects will appear from the detailed description to follow and from the appended claims.

In the drawings, in which I have illustrated several embodiments of my invention—

Figure 1 is a sectional view illustrating my invention.

Fig. 2 is a section on the line 2—2 of Fig. 1.

30 Fig. 3 is a section on the line 3—3 of Fig. 2 showing the manner in which the binding post screw is secured to the center contact;

Fig. 4 is a perspective view of the center contact;

35 Fig. 5 is an axial section of a modification of my invention;

Fig. 6 is a section on the line 6—6 of Fig. 5;

40 Fig. 7 is a plan view of the socket removed from the feed circuit, showing the split sleeve at the upper end of the socket;

Fig. 8 is a perspective view of the center contact shown in Figs. 5 and 6;

45 Fig. 9 shows an axial section of another form of socket embodying my invention.

Fig. 10 is a section on the line 10—10 of Fig. 9 showing the threaded contact shell cut away opposite the binding screw for the center contact;

50 Fig. 11 is a perspective view of the insulating base showing the U-shaped projection forming a backing for the center contact;

Fig. 12 is an axial section of a lamp socket 55 showing another form of my invention;

Fig. 13 is a section on the line 13—13 of Fig. 12;

Fig. 14 is a section on the line 14—14 of Fig. 12;

Fig. 15 is a section on the line 15—15 of Fig. 12;

Fig. 16 is a perspective view of the center contact; and

Fig. 17 is a perspective view of a modification of the center contact in which the contact member is not provided with a slot.

Referring now to the drawings in detail, and first to the modification of Figs. 1 to 4 inclusive, the feed or supply circuit comprises an inner insulated conductor 9, an 70 outer bare grounded conductor comprising a pipe 10 loosely surrounding the conductor 9 and having a threaded end 11 for engagement with an internally threaded bushing or sleeve 12 of a socket which bushing 75 is secured to the casing 13 which surrounds the insulating base 14 which supports the center contact of the lamp socket. The bushing 12 is held in properly adjusted position on the pipe 10 by means of a set screw 80 15 threaded in an opening in the bushing and engaging the end of the pipe 10. The bushing 12 is provided at its lower end with a hollow split rivet portion 16 for engagement with a correspondingly shaped split 85 portion 17 of the casing 13, alternate sections 18 and 19 of the split portions being bent over farther than the adjacent sections to prevent relative rotation between the casing and bushing. The casing 13 adjacent 90 the split portion 17 is bent so as to partially surround a re-inforcing washer 21 which not only re-inforces the casing, but serves as a backing to prevent injury to the casing when the rivet portions 18 and 19 95 are split and bent down. The casing comprises a cylindrical portion 22 surrounding the insulating base 14 and a threaded shell contact 23 for engagement with the threaded contact of the lamp base, which threaded portion 23 may also form a support for a shade holding device 24 as shown in Fig. 1. The casing 13 is beaded outwardly as shown at 25, above the threaded portion 23 to limit the distance to which the shade holding device 24 can be screwed onto the socket. After the insulating base 14 is slipped in place in the casing 13 the casing is beaded 100 inwardly, as shown at 26, to hold the base 14 firmly and permanently within the cas- 105

110

ing. The insulating base 14 is provided with a recess 27 in its upper face to accommodate the split portions 16 and 17 of the bushing and casing. The base 14 is also 5 provided with a small recess 28 on its upper face into which a portion of the casing 13 is forced, as shown at 29, to prevent relative rotation between the casing and base. A center recess 30 is also provided in the base 10 14 to accommodate the insulation surrounding the inner conductor. A central passage 31 leads from the recess 30 to permit the passage of the wire from the inner conductor. A center contact 32 of the socket comprises 15 a U-shaped spring contact portion 33 which is offset from the base portion 34 to permit the wire from the inner conductor to be led out sidewise from the central opening 31. The base portion 34 has an opening 35 through which extends a bolt 36 provided with a nut 37 non-rotatably seated in a recess 38 in the upper face of the base 14 whereby the center contact is secured to the base. The base 14 is provided with a 20 25 U-shaped projection 39 forming a backing for the U-shaped contact portion 33. A binding screw 40 extends through an opening 41 in the base 34 and is provided with a nut 42 non-rotatably held in a recess 43 in 30 the lower face of the base 14. The wire 44 from the inner conductor 9 is led through the opening 45 in the U-shaped center contact 33 and is wound around the binding screw 40 as shown in Figs. 2 and 3. The 35 circuit from the insulated conductor 9 through the socket and lamp to the grounded conductor 10 is through the wire 44, base 34, center contact 33, lamp circuit, threaded contact 23, casing 22 and bushing 12 to the pipe 10, it being noted 40 that the bushing 12 not only serves to mechanically connect the socket with the pipe 10 and support it thereon, but also serves as part of the electrical connection between the 45 threaded contact of the lamp base and the grounded outer conductor 10.

In the modification of Figs. 5 to 8, the feed circuit comprises an inner insulated conductor 46 and an outer grounded conductor comprising a coil of wire 47 wound around the inner conductor and forming a 50 sheath or armor for the inner conductor as well as a ground return. The socket comprises a casing 48 for the insulating base 49, the upper portion of the casing 48 being provided with a tapering threaded neck or sleeve portion 50 which is split, as shown at 51, to permit its being clamped tightly on the outer conductor to hold it firmly in 55 place and to secure a good electrical connection. A tapered nut 52 may be screwed down on the sleeve portion 50 after the latter is screwed or slipped in place on the outer conductor 47, the nut 52 forcing the 60 65 split portions of the sleeve 50 into firm contact with the conductor 47 as it is screwed down. A set screw 53 is threaded through the nut 52 into engagement with the sleeve 50 to hold the nut 52 in adjusted position. The casing 48 also comprises a threaded shell contact 54 for engagement with the threaded contact of the lamp. After the insulating base 49 is slipped into the casing 48 the casing is beaded inwardly as shown at 55 to hold the base in the casing. A bead 56 is also provided above the threaded portion 54 to limit the distance to which the shade holding device may be screwed onto the socket. The upper face of the insulating base 49 is provided with a small recess 58 into which a portion of the casing 48 is forced to prevent relative rotation between the casing and base. The base 49 also has a central recess 60 in its upper face to accommodate the insulation 80 on the inner conductor 46. An opening 61 extends from the recess 60 through the base 49 through which the wire from the conductor 46 extends. The center contact of the socket 62 comprises a U-shaped contact portion 63 which is off-set from the base portion 74 to permit the wiring from the conductor 46 to be led out sidewise from the opening 61. The base 74 comprises a tongue portion 75 having an opening 76 through 95 which extends a hollow rivet 77 which also extends through the opening 61 and is riveted over at its ends to hold the center contact 62 firmly on the base 49. A binding screw 78 extends through an opening 79 in the base 74 and is provided with a nut 80 which is non-rotatably held in a recess 81 in the lower face of the base 49. The base 74 is provided with a struck up portion 82 to hold the end of the wire from the conductor 46 in place after it is wound around the binding screw 78. The insulating base 49 is provided with a projection 83 which serves as a backing for the U-shaped spring contact 63. 100 105 110

The circuit in this modification from the inner conductor 46 to the outer grounded conductor 47 is through the center contact 62, lamp circuit, threaded contact 54, casing 48 and sleeve 50 to the grounded conductor 47. 115

In the modification of Figs. 9, 10 and 11 the feed circuit is the same as in the modification of Figs. 5 to 8 and the insulating base and center contact and connections are also the same. 120

I have shown, however, a modified form of the means for holding the insulating base 49 in place in the casing 84. The casing 84 is provided with a bead with which 125 engages a bead 85 formed on the threaded contact 86, the bead 85 being formed after the base 49 and threaded contact 86 have been slipped into place in the casing 84, the upper edge 87 of the contact 86 engag- 130

ing the lower face of the base 49 to hold the latter firmly in position in the casing. The threaded contact 86 is cut away as shown at 88 in Figs. 9 and 10 to prevent short circuiting between the connections with the center contact 62 and the threaded contact 86. The lower portion of the casing 84 may be provided with a bead 89 for use in connecting a shade holding device.

10 In this modification the circuit from the inner conductor 46 to the outer grounded conductor 47 is through the center contact 62, lamp circuit, threaded contact 88, casing 84 and sleeve 50 to the grounded conductor 47. In wiring all of the modifications of sockets so far described the socket is brought into position with respect to the feed circuit with the wire from the inner insulating conductor 9 extending through

15 the central opening in the insulating base after which the socket is rotated to thread the bushing onto the threaded end of the outer grounded contact, the fact that the opening through the insulating base

20 through which the wire from the inner conductor extends is central of the insulating base permitting this rotation of the socket without distorting the wire. It will be noted, too, that in all of the modifications so far

25 described the center contact is provided with an opening through which the wire from the inner conductor may extend whereby the wire from the inner conductor may be easily threaded through the opening in the insu-

30 lating base and the opening in the center contact. After the socket is screwed into position on the outer conductor the wire from the inner conductor is bent over and wound around the binding post to secure it

35 in engagement with the center contact.

40 In Figs. 12-17 I have shown a still further modification of socket in which the feed circuit includes a center insulated conductor 90 and an outer thin sheath of metal forming a ground return. In this modification the socket instead of being screwed onto the outer conductor, is slipped over the neck of a supporting base and the necks of both the socket and base are clamped onto the outer

45 conductor by means of a clamping ring.

50 In this modification I have also shown a form of center contact in which the usual binding screw is dispensed with. The supporting base 92 comprises a flat plate 93 having a number of openings 94 through which screws may be inserted for securing the base in position, and a sleeve or neck portion 95 which is split as shown at 96 (Fig. 13) to permit of its being clamped tightly on the

55 outer conductor 91. The socket casing 97 comprises a neck or sleeve portion 98 engaging and surrounding the neck portion 96 and is split as shown at 99 (Fig. 13) to permit of its being clamped tightly on the neck 95.

60 A clamping band 100 surrounds the neck

98 and is provided with ears 100^a through which extends a clamping bolt 101 for drawing the ears together to clamp the socket and base firmly on the outer conductor 91 to afford a good electrical connection there-
70 with. The upper end of the neck 98 is flanged over slightly to engage the upper edge of the clamping band 100 to prevent the socket from slipping out of the clamping band. The socket comprises a threaded
75 shell contact 103 for engagement with the shell contact of a lamp base, a bead 104 being provided above this threaded portion for engagement with the upper edge of a shade holding device. A bead 105 is also
80 provided to hold the insulating base 49 in position.

The upper face of the insulating base 49 is provided with a central recess 106 to accommodate the insulation on the inner conductor 90. A rectangular opening 107 leads from the recess 106 through the insulating base 49 to provide a passage for the wire from the inner conductor and also to permit of the connection of the center contact. 90 A pair of inclined shoulders 108 are provided on opposite sides of the upper end of the passage 107 for holding the center contact in place. The center contact comprises a middle contact portion 109, substantially 95 circular, having a slot 110 through which the wire from the inner conductor 90 is threaded when the socket is being placed in position. Extending from opposite sides of the middle contact portion 109 is a pair 100 of arms 111 provided at their upper ends with outwardly inclined portions 112 for engagement with the inclined shoulders 108. The length of the arms 111 is such that when the center contact is slipped into position in the opening 107 a space will be left between the lower part of these arms and the insulating base 49 to permit the end 113 of the wire from the inner conductor 90 to be bent over and wound around the 110 arms 111. As heretofore described, the opening 107 is rectangular in cross section so that the center contact 109 will be prevented from twisting around in the opening as the wire 113 is wrapped around it. 115

In Fig. 17 I have shown a modified form of center contact having a middle contact portion 114 substantially circular which is not provided with an opening. From opposite sides of this middle portion 114, arms 120 115 extend upwardly and terminate in oppositely inclined portions 116 for engagement with the shoulders 108. When this form of center contact is used the wire 113 is threaded through the insulating base and bent over to one side before the center contact is placed in position. After the center contact is placed in position the end 113 is wrapped around the center contact as in the modification of Figs. 12, 14 and 16. In 130 125 130

this modification the circuit from the insulated conductor 90 to the grounded conductor 91 is through the wire 113, center contact 109, lamp circuit, threaded contact 103, casing 97 and sleeves 98 and 95 to the grounded conductor 91.

- In all of the modifications it will be noted that the casing for the insulating base which supports the center contact forms a part of the return circuit and is electrically connected with the outer grounded conductor and also with the threaded shell contact which engages the shell contact of the lamp base.
- It will be noted that in all the modifications the casing of the lamp socket is mechanically and electrically connected with the outer grounded conductor by means of a sleeve surrounding the grounded conductor.

It is obvious that it is not necessary that the outer grounded conductor should surround the inner insulated conductor throughout its length, but that it may be grounded in any suitable manner.

This application is a continuation, so far as common novel subject-matter claimed herein is concerned, of my Patent No. 1,154,963, dated September 28, 1915, separable attachment plugs, application for which was copending with this application and was filed November 21, 1908.

Having thus described my invention what I claim as new and desire to secure by Letters Patent is:—

1. A lamp socket comprising an insulat-

ing base having a substantially central opening therethrough for a feed wire, a center contact supported by said insulating base, said center contact comprising a U-shaped portion between the arms of which the said wire is to extend and a wiring terminal supported by said center contact.

2. A lamp socket comprising an insulating base having a substantially central opening therethrough for a feed wire, a center contact supported by said insulating base, said center contact comprising a U-shaped portion between the arms of which the said wire is to extend, a binding plate portion to which the end of said wire is to be secured and a wiring terminal for securing said wire.

3. A lamp socket comprising an insulating base having an opening therethrough for a feed wire, a center contact, means for securing said center contact to said base comprising a hollow rivet extending through said opening, said center contact comprising a U-shaped contact portion, a base struck up from said U-shaped portion, said base having an aperture through which said hollow rivet extends and a wiring terminal supported by said struck-up base.

In witness whereof, I have hereunto subscribed my name in the presence of two witnesses.

REUBEN B. BENJAMIN.
